ELECTRICAL CONNECTER

Robert E. Farish, Jr., Columbus, Ga.

Application November 23, 1932, Serial No. 644,097

2 Claims. (Cl. 173—343)

This invention relates to improvements in electrical connectors and has particular reference to a connector of the separable type such as used in making connections for lamps, heaters, irons and other electrical appliances.

In one type of separable connector most universally used, the plug member is provided with two prong terminals which are insertable into corresponding openings formed in the socket member in order to establish an electrical circuit through the connector. It is well known that difficulties are experienced particularly in certain circumstances in joining the members of the connector, such as the inconvenience of aligning the terminals with the openings when joining the members and the fact that with the members already joined the socket members cannot subsequently be threaded into a receiving socket without twisting the conductors connected to the plug member.

Other types of connectors have also been devised in which the plug member is provided with a central or axial post for making one of the contacts, and with a separate member to one side of the axial member or entirely surrounding the axial member so that when this is inserted into the socket which has a corresponding central contacting member for engaging the post and an annular side member for engaging the other conductor, it will not make any difference whether the parts are rotated to exactly the same point each time as before the plug is inserted, because the contacts will be properly made regardless of the relative rotary position of the plug with respect to the socket. It has also been discovered that by making the central opening in the socket larger at its outer end than at its inner end, it will be much easier to insert the central post into the socket in the proper manner.

However, in both of the two last mentioned means, the central opening in the socket has contained at least one electrical contact which is alive at all times that the socket is in place, and has at all times another live contact exposed, so that if some metal object were accidentally dropped or pushed into the socket, a short circuit might very easily be caused and result in the blowing out of fuses and other inconveniences, if not in fact in more serious consequences.

It is therefore one of the objects of this invention to provide an electrical connection of the type under discussion, in which the plug may be inserted into the socket in any relative rotary position desired, in which the aligning of the plug with respect to the socket is rendered as

easy as possible, and in which there are no exposed contacts of the socket member which could be short circuited by a metal member not made particularly to accomplish that purpose. Another object is to overcome the disadvantages previously experienced in connection with the prior art devices.

Yet another object is to provide a socket member for an electrical connection, which socket member can be left in the electrical circuit without the plug inserted therein, without any fear that some foreign member might be accidentally inserted in the socket and cause a short circuit.

Another object of this invention is to provide a simplified and more efficient form of electrical connection of the type described.

The above and other objects will appear more clearly from the following detailed description when taken in connection with the accompanying drawings which illustrate by way of example one means for carrying out the objects of this invention. It is to be clearly understood that the following description and accompanying drawings are by way of illustration, and are not to be taken as in any way limiting the scope of this invention. The scope of this invention is to be limited only by the prior art and by the terms of the appended claims.

In the drawings:

Figure 1 is a sectional view of an electrical connector selected for the purpose of illustration, showing the parts in their assembled relationship;

Figure 2 is a view illustrating a cross section of the socket member;

Figure 3 is a similar view illustrating a cross section of the plug member; and

Figure 4 is a similar sectional view showing the thimble or cap member used for concealing the electrical connections on the plug member.

Figures 5, 6 and 7 are views similar to Figure 1 showing modified forms of this invention.

Referring now more particularly to the drawings in which similar numerals indicate corresponding parts, the numeral 1 indicates the inner plug member which is formed from some insulating material such as hard rubber or other suitable compound. This plug member is formed with a frusto-conical portion 2 having partially embedded in its outer apex portion a suitable electrical contact post 3, the end of which projects outwardly, and terminates in a ball member 4, or other suitable shape.

Adjacent the base of the frusto-conical portion, the plug member is slotted as at 5 to re-

ceive an electrical contact ring 6 for the purpose of establishing the other electrical connection necessary in a device of this type. The annular member or ring 6 is arranged concentrically 5 with respect to the contact post 3, so that all of its parts are equi-distant from the said post. As shown in the drawings also, the post 3 projects outwardly a considerable distance further than the ring 6 for a purpose to be described 10 hereinafter.

The base portion of the plug 1 is in the form of a cylinder threaded on its outside as shown at 7 in Figure 3. Two binding posts 8 and 9 respectively, or other suitable electrical connecting 15 means are provided in the base of the plug. The binding post 8 as shown is connected by means such as the conductor 10 embedded in the plug member, with the contact post 3, and the binding post 9 is connected by a similar conductor 20 11 to the annular contact ring 6. The lead wires from the electric iron or other electrical appliance to be connected, are connected preferably to the binding posts 8 and 9 respectively.

After the wires just mentioned have been connected to the binding posts, the thimble or cap member 12, having internal threads at 13 adapted to engage the threads 7 on the plug member 1, is screwed in place to conceal the connection of the wires from the attachment to the binding 30 posts 8 and 9 as just described. These wires pass out of the thimble 12 through the opening 14 provided for this purpose.

Turning now to the socket member 15 as clearly set forth in Figure 2 of the drawings, it will be seen that this socket member is provided with an inner conical recess portion 16 adapted to receive the conical portion 2 of the plug 1. At the base of this conical recess portion there is provided a cylindrical depression 17, in which is 40 contained a U-shaped spring member 18 adapted to make contact with the post 3 and securely hold the portion 4 between the prongs 19 and 20. As will be distinctly noted in the drawings, this U-shaped contact member is secured in the recess 17 by means of the screw member 21 which passes through the opening 22 in the socket member. It is usually desirable to provide a washer member 23 underneath the head of the screw 21 as illustrated.

50 In position to receive the ring or annular member 6 of the plug, the socket 15 is provided with an annular recess 24, in which there is positioned a contact ring or annular member 25 for the purpose of making contact with the contact ring 6. The ring 25 is connected by means of a conductor 55 26 passing through the body of the socket member to a sleeve member 27 surrounding the outer portion of the socket member. As will be seen, this sleeve 27 is formed with threads adapted to 60 fit into the standard electric light socket having a threaded connection. As is well known, in this type of socket, the other contact member is in the bottom and center of the socket, in such position that when the member 15 is screwed into 65 such a socket the sleeve 27 will form one of the contacts with the socket member, and the screw head 21 will form the other contact.

It will be seen therefore that when the plug member 1 is inserted into the opening in the 70 socket member 15, the portion 4 of the contact post 3 will be snapped between the prongs 19 and 20 of the U-shaped contact member 18 which will form an electrical connection between the binding post 8 and the head of the screw 21, and also 75 firmly secure the plug member in place in the

socket. At the same time that this electrical connection is formed, it will be seen that the ring member 6 will be received into the socket or recess portion 24 and will make contact with the ring 25, thereby forming a complete electrical connection between the binding post 9 and the threaded sleeve 27.

It will be appreciated that other wire attaching means than binding posts might be used in place of members 8 and 9. It is therefore to be understood that whenever the term "binding post" is mentioned in this specification or in the claims it is to be taken as including any equivalent structure for performing the same function.

In Figures 5, 6 and 7 of the drawings there are 15 illustrated various modifications of this invention. In all of these figures for instance, the threaded sleeve 28, corresponding to the threaded sleeve 27 of Figures 1 and 2, is shown placed over a cylindrical portion 29 of the socket member 30, 20 instead of being placed over a threaded portion as in Figures 1 and 2. In order to secure the member 28 over the cylindrical portion 29, extensions 31 are formed at the outer end of the member 28 and are bent over the end of the cylindrical portion 29 and secured to the same by means of a screw 32 or similar suitable means.

In Figure 5 also there is illustrated a thimble 34 preferably made of metal which may be used instead of the thimble 12 shown in Figure 4. 30 This thimble 34, as shown, instead of being threaded on to the base portion of the plug as illustrated in Figure 1, may be secured thereto by means of a pair of screws 35. This construction has the advantage of being cheaper to make, and 35 at the same time being less bulky than the thimble shown in Figure 4. It is formed with an opening 36 corresponding to the opening 14 in the thimble 12.

Also in Figure 5, the annular contact members 40 have been made in the form of springs 37 and 38 having interengaging portions 39 and 40 whereby they may be positively held together.

In Figure 6, the annular contact members are 45 shown in the form of solid rings 41 and 42, adapted to slide one inside the other when the two parts of the connector are placed together. These rings are preferably formed one with a slightly recessed portion 43, and the other with a small 50 tit 44 to engage in the recess.

Figure 7 shows the contact member in the socket portion of the connection as being a solid ring 45, whereas the contact member on the plug portion is made in the form of a spring ring 46 which is adapted to resiliently engage the side of 55 the solid ring 45 when the two members are brought together as above described. In order to facilitate the formation of the ring 46 with the bent over portions 47, it may be found desirable to make the portions 47 in the form of a 60 plurality of separated tongues integrally formed with the member 46. This will allow the finished member to have more springiness or resiliency so that it may more positively engage the ring 45.

It is to be noted in connection with the various 65 forms set forth that the slot in which the annular member on the socket is positioned, is narrow enough so that the ball 4 on the end of the post 3 will not enter the same, but will slide over the same as it comes in contact with it, and the 70 process of inserting the plug in the socket will not be interfered with. It will also appear, that by the construction shown in Figure 2, it becomes impossible to bring the ball 4 in contact with the annular ring in the socket 25, and it is equally 75

impossible to bring the annular ring 5 in contact with the spring clip member 18.

It will be seen also from the above that the arrangement of the contact members 18 and 25 in the socket member 15 is such that both of these members are recessed or countersunk into the member 15, in such a manner that a short circuit could not be formed unless a metal or other electrical conductor member were bent so as to fit into both of the depressions at the same time. Obviously, a single foreign body thrust into the socket either by accident or otherwise, could not form a short circuit as it might if the ring 25 for instance extended outside of the annular recess portion 24.

It will also be apparent that by virtue of the conical shape of the portion 16 of the socket member, the contact post 4 which is the first part of the plug member to enter the socket member, will be guided downwardly and enter the portion 15 with practically no expenditure of effort in aligning the terminals.

From the above description it will be perceived that a means has been provided for carrying out the objects of this invention in a very advantageous and desirable manner.

As pointed out above however, other forms and embodiments of my invention may be availed of, and therefore it is to be distinctly understood that this invention is to be limited only by the prior art and by the terms of the appended claims.

Having described my invention I claim:

1. In an electrical connection, a plug member of insulating material, concentric axial and annular contact members projecting therefrom in an axial direction, the axial contact member projecting farther than the annular member, a socket member of insulating material having an unobstructed socket formed therein, said socket being of gradually decreasing cross section from the outer toward the inner end thereof, the outer end of said socket being of greater diameter than the annular contact member projecting from said plug member, and the inner end of said socket merging with an axially extending axial recess formed at such inner end, said socket member
2. In an electrical connection, a plug member of insulating material, concentric axial and annular contact members projecting therefrom in an axial direction, the axial contact member projecting farther than the annular member, a socket member of insulating material having an unobstructed socket formed therein, said socket being of gradually decreasing cross section from the outer toward the inner end thereof, the outer end of said socket being of greater diameter than the annular contact member projecting from said plug member, and the inner end of said socket merging with an axially extending axial recess formed at such inner end, said socket member

having an annular groove formed in the wall of said socket and extending from such wall in a direction parallel to the axis of the plug, said groove being of a diameter to receive said annular contact member on the plug member but of such size as to exclude the axial contact member, an axial contact member disposed entirely within said axial recess and adapted to receive and make contact with said axial contact member on the plug member, and an annular contact member disposed entirely within said axially extending annular groove and adapted to receive and make contact with said annular contact member on the plug member.

2. In an electrical connection, a plug member of insulating material, concentric axial and annular contact members projecting therefrom in an axial direction, the axial contact member projecting farther than the annular member, a socket member of insulating material having an unobstructed socket formed therein, said socket being of gradually decreasing cross section from the outer toward the inner end thereof, the outer end of said socket being of greater diameter than the annular contact member projecting from said plug member, and the inner end of said socket merging with an axially extending axial recess formed at such inner end, said socket member having an annular groove formed in the wall of said socket and extending from such wall in a direction parallel to the axis of the plug, said groove being of a diameter to receive said annular contact member on the plug member, an axial contact member disposed entirely within said axial recess and adapted to receive and make contact with said axial contact member on the plug member, an annular contact member disposed entirely within said axially extending annular groove and adapted to receive and make contact with said annular contact member on the plug member, and said axial contact member on said plug being of such size as to prevent its entry into said annular groove in the socket member while being guided into the axial recess by the walls of said socket.

ROBERT E. FARISH, JR.
